WILLIAM A. BUCKNER, OF FRESNO, CALIFORNIA

SELF-CLOSING VALVE

Application filed May 3, 1928. Serial No. 274,805.

This invention relates to sprinkler systems such as are installed in connection with golf courses and similar areas, which utilize underground piping and sprinklers connected thereto at intervals and which must be removed when sprinkling operations are completed so that nothing will then project above the ground.

The principal object of my invention is to provide a self-closing valve adapted to be permanently connected to the underground pipe, and a quick detachable coupling member to cooperate with the valve for opening the same.

Another object is to arrange the coupling structure so that there is no sideways movement thereof nor any partial rotation necessary to effect the coupling, but only a straight downward pressure which is obtained in conjunction with the movement of the coupling lever to a locking or clamping position.

A still further object is to construct the plunger of the valve in such a manner that it may be easily adjusted to enable the volume of flow therethrough to be altered, without affecting or having to adjust the coupling device itself.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved valve and coupling shown as mounted in place in connection with a pipe line and sprinkler.

Fig. 2 is a vertical section of the valve and coupling shown as associated together but before the coupling is locked to the valve.

Fig. 3 is a similar view showing the coupling as locked.

Fig. 4 is a sectional view of the valve plunger showing the flow adjustment feature.

Fig. 5 is a fragmentary view of a sprin-

kler barrel showing the coupling member as formed integral therewith.

Referring now more particularly to the characters of reference on the drawings, the numeral 1 denotes the stationary barrel of a sprinkler 2 of the slow rotation type such as is shown in my copending application for patent, Serial No. 88,550, filed February 16, 1926, and others of a like nature, whose lower end is adapted to be screwed into the coupling member. The coupling member comprises a tapped sleeve portion 3 to screw onto the barrel and a straight or plain sided tubular member 4 depending therefrom and concentric therewith. A compressible gasket 5 is placed about the member 4 at the junction of the same with the sleeve 3.

The member 4 is adapted to snugly but removably fit into the neck portion 6 of a valve body 7, the body below the neck being bored as at 8 to a diameter greater than the bore of the neck. Slidable in the bore 8 is a plunger 9, which on its upper end carries a reduced portion 10 to snugly fit the neck. A gasket 11 about the base of the portion 10 is adapted to fit against the bottom or base of the neck to normally maintain a water tight fit therewith, the plunger being held to this position by a spring 12 in the bore below. The spring bears at one end against the plunger and at the other end against a removable reducing bushing 13 by means of which the valve is attached to a nipple 14 projecting upwardly from the underground pipe line 15 as shown in Fig. 1.

The body 7 has opposed vertical or longitudinal bypasses 16 communicating with the enlarged or main bore 8 both at top and bottom thereof. The body 9 of the plunger is solid, but the upper portion 10 is hollow, being open to the top and having lateral openings 17 intermediate its top and bottom communicating with the hollow area. Adjustably mounted in the plunger body is an upstanding screw 18 whose head 19 projects into the upper hollow area intermediate the top and bottom of the openings 17, and is approximately the same diameter as the bore of said hollow portion. By means of this construction it will be seen that the valve is normally

closed owing to the upward pressure of the spring; but when the plunger is depressed so that the lateral openings 17 register with the upper ends of the bypasses, water can flow from said bypasses to the coupling member above through such openings. This flow, however, can only take place through the portion of the area of the lateral openings which are above the screw head 19. This is on account of the close fit of the screw head with the bore of the member 10, which prevents the upward movement of any appreciable amount of water entering the lateral openings below said screw head. It will therefore be seen that adjusting the screw 18 up or down, alters the area of the lateral openings available for the passage of the water, so as to give different volumetric flows of water, with the same amount of depression of the plunger. The length of the member 4 of the coupling is such that when the gasket 5 is compressed against the top of the neck 6, the valve plunger will be depressed so that the full height of the lateral openings register with the top ports of the bypasses as shown in Fig. 3. Also the length of the neck and correspondingly that of the member 4 is sufficient to provide a firm bearing between these parts and prevent any possible lateral or rocking movement therebetween.

The valve being opened by a straight downward pressure of the member 4 on the plunger, the latter is not turned or canted so as to tend to cause it to bind or the gasket to be cut. The bypass arrangement provides for a flow of water through the valve which will not be affected by the movement of the body of the plunger and allows the latter to be solid as is necessary in providing my improved form of flow control adjustments.

The coupling member 4 is depressed and clamped in position in the neck so as to maintain the plunger valve open and the valve and coupling in rigid relationship by the following means: A handle lever 20 has a yoke 21 which is pivoted on the opposite sides of the coupling member 3. Depending from the handle end of the yoke are locking cams 22 which are adapted when the handle is swung downwardly from a substantially vertical position, to pass under and clampingly engage opposed lugs 23 projecting outwardly from the valve body. The lug engaging edges of the cams are so disposed relative to the pivot of the yoke that the outer ends of these cams are further from the pivot than their inner ends. Therefore as the handle is depressed the cams engage the lugs with increasing pressure, and the coupling member is drawn straight down until the gasket 5 is firmly compressed against the top of the valve body, said cams being then in locking position with the lugs. This structure itself is substantially the same as that shown in my

co-pending application for patent, Serial No. 191,709, filed May 16, 1927. Due to the fact that the member 4 projects a considerable depth into the neck of the valve, there can be no side play between the parts after the locking compression has been attained, as previously stated, and consequently no matter how much lateral pull or strain may be placed on the coupling, the joint will be maintained tight and leak proof.

By reason of the above arrangement of parts, the coupling having a close fit with the valve and being pressed down straight into both a clamping and plunger depressing position with a downward pressure on the handle, the coupling may be made instantly and there will be no squirting of water from the structure as the plunger becomes depressed. This feature in connection with the slow rotation type of sprinkler used, enables the operator to attach the sprinkler to the valve and get clear of the latter without being sprayed by water from the sprinkler or from between the valve and coupling.

The valve body is provided with a hinged cover 24 so that after the coupling is removed the cover may be swung over the top of the valve to close the neck and prevent dirt and other foreign matter from lodging in the same.

In the above I have described the coupling member as being a unit in itself capable of being attached to any sprinkler but not necessarily permanently connected thereto. If desired, however, I may make the coupling member 4^a an integral part of the base of the sprinkler barrel 1^a, and mount the locking lever 20^a directly on said base as shown in Fig. 5, so that the valve and sprinkler form the complete cooperating apparatus.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A valve comprising a body having a main bore and a reduced neck bore beyond the main bore, a plunger closely slidable in the main bore and normally seating against the base of the neckbore to close the same at said base, and a longitudinal bypass formed in the body and communicating with the main bore at both ends thereof whereby when the plunger is depressed from its seating position, water may pass from the main bore beyond one end of the plunger to the neck beyond the other end of the same.

2. A valve comprising a body having a main bore open to the outer end of the body and a reduced neck bore beyond the main bore, means at said end of the body adapting the same for connection to a supply pipe, a plunger in the body comprising a solid body portion slidable in the main bore and a hollow reduced portion open to its outer end and slideable in the neck, means normally maintaining the body of the plunger seated against the base of the neck to seal the same from the main bore, the hollow portion of the valve having lateral openings, and water passage means in the body communicating with one end of said main bore, and adapted to register with said lateral openings when the plunger is depressed.

3. A valve comprising a body having a main bore and a reduced neck bore beyond the main bore, a plunger in the body comprising a solid body portion slidable in the main bore and a hollow reduced portion open to its outer end and slideable in the neck, means normally maintaining the body of the plunger seated against the base of the neck to seal the same from the main bore; the hollow portion of the valve having lateral openings intermediate its outer and inner ends, water passage means in the body communicating with one end of said main bore and adapted to register with said lateral openings when the plunger is depressed, and means for altering the area of the openings through which the water may pass from said passage means to the neck with the same extent of depression of the plunger.

4. A structure as in claim 3, in which said last named means comprises a longitudinally adjustable head in the hollow portion of the plunger; said head being substantially the same diameter as the bore of said portion and being located intermediate the outer and inner ends of the lateral openings.

In testimony whereof I affix my signature.
